O. OLSEN

NAIL SET

Original Filed Feb. 23, 1926

UNITED STATES PATENT OFFICE.

OLE OLSEN, OF SEATTLE, WASHINGTON.

NAIL SET.

Refiled for abandoned application Serial No. 89,946, filed February 23, 1926. This application filed February 29, 1928. Serial No. 257,841.

My invention relates to nail sets, particularly such as are used by floor layers in setting the finishing nails within the wood of floor boards.

5 Ordinarily, using a plain nail set, the workman must grasp it tightly near the tip, gauging its distance above the floor and positioning it relative to the nail with a finger, after which it must be struck sharply 10 while so held, to the end that it will bite into the head of the nail and drive the nail the proper distance below the surface of the floor. One result of the firm grasping of the nail set is cramping of the fingers, requiring 15 frequent resting, and lessening the work possible of accomplishment. The repeated striking of the hammer, with the set so firmly grasped, causes a shock to the hand and to the entire system. A result of using 20 the finger as a gauge is that occasionally the finger is pinched and seriously injured. Further, as the result of occasional carelessness, generally brought about by fatigue resulting 25 from the above causes, the nail set sometimes slips and mars the floor, or is struck a glancing blow and breaks.

One of the objects of my invention, then, is to provide means whereby the nail set will automatically be positioned properly relative to the floor and to the nail being set, without the necessity of the workman grasping the nail set and guiding it with his own fingers. Associated with this object, it is a further object to position the nail set properly and so that its point is clearly visible 30 at all times. It is also a further object, by thus positioning the nail set and by avoiding the necessity of grasping the nail set itself, to protect the workman's fingers from being 35 pinched between the nail set and the floor.

40 Another object is the positioning and guiding of the nail set in such a way that it is not likely to be struck a glancing blow, which, as explained above, tends to break the highly tempered sets, thus prolonging their life.

45 A further object is the provision of means which will exactly gauge the amount of setting and which can be adjusted to vary the same.

50 Other objects, and especially those which relate to structural details, will be easily ascertained from a study of the drawings, wherein my invention is shown embodied in forms which are now preferred by me, and 55 of this specification and the claims terminat-

ing the same, wherein the features which constitute my invention are defined.

Figure 1 is an elevation with parts in section of a preferred form of nail set.

Figure 2 is a similar view of a modified 60 construction.

Figure 3 is a side elevation of a further modification and Figure 4 is a plan view of the same construction.

Essentially my idea comprises the provision of a frame, with which is preferably associated a standard nail set, slightly or not at all modified, so combined that the frame alone is freely and naturally held, and so that the nail set need not be grasped directly, 70 but is held and positioned at a proper distance above the floor and above the nail to be set, in a properly vertical position, and with the tip of the nail set and the head of the nail always visible so that the nails may 75 be set rapidly, accurately, with little exertion on the part of the workman, and all at uniform depths.

It is to be understood that my device is not, *per se*, a positioning means, but rather 80 a gauge and a handle, in other words it is not my intention, by the use of this device, to position the nail set with respect to the head of a nail, but rather to afford a convenient means of holding the nail set in such 85 a way that it can be positioned by visual means, the set being visible from substantially all directions, and to provide, further, a means which will gauge the distance of the nail set above the head of the nail. 90

In the preferred form shown in Figure 1, a standard nail set 1, which may be round in cross section, is held in a frame, or guide, consisting of the tube or sleeve 2, having the upwardly opening aperture 20 and supported 95 by legs 23, which are spaced from each other at opposite sides of the tip 11, of the nail set 1. The nail set 1, as will be seen, extends through a bore 25 in the main frame below the chamber 20 and is guided in this bore 100 25 for substantially vertical movement when the entire frame is held in vertical position. It is normally held in upraised position by such means as the spring 4, seated within the chamber 20 and supporting the nail set 105 through the medium of a flange or collar 13 and a spring cup or washer 41. Upward movement of the nail set, under the influence of the spring 4, is limited in some suitable fashion as by the provision of a nut 3 110

threaded at 24 within the upper end of the chamber 20. This may be held in adjusted position by a set screw 30 and the upper end of the nail set may protrude through a bore 31, in the nut 3, which is aligned with the bore 25.

Now the lower end of the legs 23, which support the sleeve 2 above the floor, may be formed in any suitable manner, as by rounding them over or otherwise, I may provide the balls 21 received in suitable sockets therefor in the end of the legs and held in place as by swaging over the edges of the sockets, thus forming in effect ball supports, or casters, for the nail set. These enable it to be moved from place to place over the surface of the floor with practically no effort.

The device is employed by grasping one of the legs 23, or the sleeve 2, placing the balls 21 in contact with the floor and moving the tool until the tip 11 of the nail set is positioned directly above the head of a nail set flush, or nearly flush, with the floor level, where the tip 11 is spaced about $\frac{1}{16}$ " above the nail head and it is to be noticed that neither the nail set nor any portion of the tool itself contacts with the nail. The nail head, however, is freely visible from all sides, except when directly in line with the legs 23, which are made thin and comparatively narrow.

Thus positioned and held by the frame, the tip of the nail set and the nail head are both within plain view of the workman and the nail set is positioned visually vertically above the nail, directly in line therewith. The upper end of the nail set, which protrudes through the bore 31, is then struck a sharp blow, whereupon its tip 11 strikes and bites into the head H and the nail is forced into the wood. Upon raising the hammer the spring 4 returns the nail set to its original position and the device is moved into position over the next nail.

It is important that the tip 11 be spaced above the nail head and not be placed in contact therewith, as it has been found that a sharp blow of the tip upon the nail head is required to prevent the tip 11 sliding off the nail head and damaging the floor, and perhaps breaking the hard and brittle nail set. It is the necessity for thus holding the nail set above the nail, gauging the distance with a finger, which is the cause of occasionally pinching the workman's fingers between the nail set and the head, with painful results. By the use of this tool, cramping due to tightly gripping the nail set is prevented and the shock is removed from the workman's hands, making it possible to continue for a longer time without resting, and to make greater speed while working.

It has been found unnecessary to provide any means for limiting the setting movement of the nail set so that the nails may be uni-

formly set, for the expert workman will generally strike a blow of just sufficient force to produce the desired set and thus no stop is required. However, if a stop were found desirable it might be provided by introducing a member within the chamber 20 with which the cup or washer 41 might contact to limit the downward movement of the nail set.

In Figure 2 is shown a device which is like the form of Figure 1, but of somewhat skeletonized construction. It still employs the legs 23, spaced apart to leave the tip 11 of the nail set 1 clearly visible, but instead of employing the sleeve 2 as a guide for the nail set the legs 23 are connected by cross bars 26 and 27, thus leaving a rectangular frame above the floor. In the upper bar 26 is threaded the nut 3 in the bore 31 of which the upper end of the nail set 1 is guided, and in the lower cross bar 27 is formed the guide 25. The spring 4 in this instance is supported between the washer 41 which contacts with a pin 14 and the upper surface of the cross bar 27. A pin 12 limits upward movement of the nail set while a pin 15 limits its downward movement. The end of the legs 23 may be formed as in Figure 1, but as shown herein are provided with rollers or wheels 22.

Figure 3 illustrates a further modification of the form of Figure 2 in that the spring 4 is placed above the upper cross bar 26. The pin 15 limiting downward movement is now placed between the cross bars 26 and 27 and contacts with the cross bar 27 to limit the downward movement of the nail set. It will be understood, of course, that in this form and in the form of Figure 2 this pin 15 may be omitted if desired, and usually would be omitted for expert setters. In Figure 3 also the end of the legs 23 are shown as provided with rounded balls 28 which contact with the floor.

In Figure 4 it will also be noticed that a third leg is provided. With a two-legged nail set, as heretofore described, the nail set is automatically held vertical in one plane, but the workman must take care to retain it vertical in the transverse plane. This is not difficult for an expert but when used by the ordinary householder it may be desirable to provide means which will enable him to avoid the necessity of retaining the nail set exactly vertical. Thus the three legs 23, 23 and 29 form a triangle support for the nail set. The construction is otherwise substantially as previously described.

What I claim as my invention is—

1. A hand tool for setting nails comprising a nail set, a frame comprising a pair of widely spaced floor engaging legs having means well above the floor for connecting said legs and guiding said nail set for reciprocal movement, and means yieldably

supporting said nail set in said frame with its tip in predetermined position above the floor and nails therein and spaced from all parts of the frame.

5. 2. A hand tool for setting nails comprising a nail set, a frame comprising a pair of floor-engaging legs, widely spaced from said nail set, said frame having means well above the floor and connected to said legs, for guiding said nail set for reciprocatory movement, a stop limiting upward movement of the nail set, and a spring acting yieldably on said nail set and cooperating with said stop to hold the nail set normally upraised, 15 and with its tip in predetermined position above the floor and nails therein and widely spaced from all parts of the frame.

3. A hand tool for setting nails comprising a nail set, a frame comprising a pair 20 of floor-engaging legs, widely spaced from said nail set, said frame having means disposed well above the floor for connecting said legs and guiding said nail set for vertical reciprocatory movement, stops limiting 25 movement of the nail set in either direction, and a spring yieldably acting on said nail set and cooperating with the upward stop to hold the nail set normally upraised, and with its tip in predetermined position above 30 the floor and nails therein, and widely spaced from all parts of the frame to be clearly visible, the downward stop limiting movement of the nail set into the floor.

4. A hand tool for setting nails comprising 35 a nail set, a frame having means guiding said nail set for reciprocatory movement, means yieldingly supporting the nail set in

said frame, and two legs depending from said frame at opposite sides of and spaced from the nail set, to contact with the floor 40 and to maintain said nail set substantially in vertical relationship to the floor and with its tip spaced above nails thereon and clearly visible between said legs and out of contact therewith. 45

5. A hand tool for setting nails comprising a nail set, a floor-engaging frame having two legs joined by cross bars, said bars having vertically aligned apertures forming guides receiving said nail set, stop pins in 50 said nail set engageable with said cross bars to limit upward and downward movement of the nail set, and a coil spring surrounding said nail set and operable to retain it normally and yieldably upraised above the 55 floor level defined by the lower ends of said legs.

6. A hand tool for setting nails comprising a nail set, a two-legged floor-engaging frame having connecting cross bars, said 60 bars having vertically aligned apertures forming guides receiving said nail set, stop pins in said nail set engageable with said cross bars to limit downward movement of the nail set and a coil spring surrounding said 65 nail set and operable to retain it normally and yieldably upraised above the floor level defined by the lower ends of said legs, and a guide bushing threaded in one of said apertures and cooperating with the downward 70 stop pin to vary the amount of setting.

Signed at Seattle, King County, Washington, this eighteenth day of February, 1928.

OLE OLSEN.
